COMBINED ADJUSTABLE COUPLING AND
SWITCH ACTUATORWayne M. Mack, Easton, Pa., assignor to Dixie
Cup Company, Easton, Pa., a corporation of
Delaware

Application December 7, 1945, Serial No. 633,478

4 Claims. (Cl. 74—69)

1

This invention relates to a combined adjustable coupling and switch actuator which, although capable of use in various types of machinery, is primarily intended for use in connection with automatic vending dispensers, such as coin control apparatus for delivering beverages or the like in suitable containers, as paper cups, the general characteristics of which machines are known in the art.

In machines of the type recited it is customary practice to provide units of the associated mechanisms through various sources and to operatively connect such units in a completed combination. Such combination requires certain alignments or registration of driving and driven shafts or members and it not only requires perfect designing and workmanship, but frequently much care and supplemental adjustments to secure the driving and driven shafts in truly workable correlation.

The fundamental characteristic of the present improvements is the provision of a self-adjusting or flexible coupling between the driving and driven members and the association therewith of an adjustable camming mechanism to constitute the actuator or control for a switch determining the operation of a part or parts, as may be desired, in the dispenser mechanism, for example, the supply of the cup adapted to receive the beverage or the like, the shifting of stacks of cups from which a cup is to be delivered, the running and stopping of the mechanism, etc.

One practical and preferred embodiment of the invention is illustrated in the accompanying drawings, forming part hereof, and the novel details of the present invention will appear from said illustration when viewed in connection with the detailed description hereinafter presented, and as embraced within the hereto appended claims.

In the drawings:

Figure 1 is a top elevation of fragmentary portions of units adapted to be coupled, (the refined mechanisms thereof not being illustrated because of their being unimportant so far as the present invention is concerned) associated through the medium of the improved coupling and switch actuator of the present invention;

Figure 2 is a vertical longitudinal section of the same;

Figure 3 is a transverse sectional view illustrating the end of the mechanism illustrated in the preceding figures and the association of the same with a switch to be actuated or controlled thereby;

Figure 4 is a detached inner face view of one of

2

the coupling members enabling the adjustment or flexibility between the same and its companion coupling member;

Figure 5 is a similar view of the other coupling member.

Referring more specifically to the drawings, wherein like reference numerals designate the same parts in the several views, 5 represents an electric motor or the like, constituting what has been styled as the driving member, that may be controlled in any conventional or preferred manner, as by a switch actuated through the medium of the depositing of a coin, for example, usual in coin control means and not shown herein.

A drive shaft 6 projects outwardly from the motor and has pinned or otherwise secured thereto at 7, a head 8, constituting one member of a coupling. A complementary or opposite head 9 of 20 said coupling is pinned or otherwise secured, as at 10, to a driven shaft 11, projecting from a part of the dispenser mechanism, diagrammatically illustrated at 12, to be actuated by the shaft 11. The drive and driven shafts 6 and 11 project towards each other and are intended to be in true alignment, but as has been previously noted, an imperfect alignment at times prevails; and a feature of the instant invention is to accommodate for such disalignment while permitting the intended drive of the shaft 11 from the shaft 6 of the motor.

To the foregoing end the head 8, on the shaft of the motor, has radially disposed on its inner face a pair of ways 13, alternatively usable, in case of wear of parts. In one of these ways, the upper one as shown in Figure 2, a guide 14 of circular contour slidably fits for movement radially of the drive shaft 6 to accommodate for any lack of true axial alignment of the shafts 6 and 11, the guide being the hollow head of a screw or bolt, the stem 15 of which is threaded into the opposite coupling member 9 as at 16. On a smooth intermediate portion 17, of the bolt, of a length to substantially span the space or separation 18, between the adjacent ends of the shafts 6 and 11, is sleeved a multi-faced cam 19, adapted to be turned on the said portion 17 to appropriately position one of the cam faces for initial operation or permit adjustment to displace the same to present another of said faces in operative position at will, dependent upon the wear of said cam faces, as will be obvious.

In the example illustrated the cross-section of the cam 19 is square, as seen in Figure 5, the corners 20 thereof constituting the operating por-

55 tions of the cam.

The cam 19 is fitted between a like square seat or recess 21, in the inner face of the coupling member 9 to prevent the cam from turning away from its position of adjustment, and it is bound in said seat or recess by the head 14 of the bolt or screw 15 impinging upon the adjoining end of the cam and securing the same in place between said head and the base of the seat 21. The head or guide 14 is hollow, as stated, and of angular contour to receive an internal wrench or tool utilized in securing the bolt 15 in binding position or loosening the same to allow for turning the cam 17 to position a new actuating corner 20 thereof in operative position, it being observed that the screw 10, binding the coupling member 9 to the shaft 11, may be loosened to permit the sliding of the coupling member 9 on its shaft 11, to separate the members 8 and 9 when it is desired to manipulate the head 14 in loosening or fastening the cam 19, said screw 10 entering an elongated groove 22 and binding upon the shaft 11, also permitting a limited adjustment of the coupling member 9 with respect to the companion coupling member 8.

The coupling members being assembled it will be appreciated that the driving of the shaft 6, by the motor, will correspondingly impart motion to the shaft 11 through its head 9 and the self-adjusting coupling means 14, 19 and 16 therebetween; and the complementary rotation of the shafts and coupling member will carry the cam 19 with its appropriate contacting corner or cam face 20 around with the shafts so that it will actuate the member or part intended to be contacted thereby, in this instance being a contact roller 23, carried at the end of a spring 24 constituting one member of a micro-switch or the like, said switch member 24 normally springing outwardly when not depressed by the cam 19 to open or close a circuit, as the case in question may demand, or make desirable. This switch member 24, with its roller 23, is clearly shown in Figure 3, from which it will be seen that as the coupling is rotated, in either direction, the radially outermost cam surface 20a will engage the roller 23 and press the same outwardly to correspondingly actuate the switch member 24, resulting in the opening or closing of the circuit, as the case may be.

From the foregoing, it will be appreciated that in a very simple, but efficient and durable mechanism, an adjustable or flexible coupling to accommodate disaligned shafts is afforded, while at the same time an adjustable actuator cam is firmly maintained and supported between the opposite members of the coupling, in position to concomitantly actuate the switch when the coupling rotates, in crank fashion, with the rotation of the driving and driven shafts 6 and 11.

I claim:

1. The combination with drive and driven members, of means for coupling the same while allowing for disalignment of said members, comprising rotatable heads having relatively radial adjustable movement therebetween, a cam carried by the coupling located between the heads and

rotated therewith, said cam being of angular contour to provide multi-faced cam surfaces, and means for rotatably adjusting the same, the head to which the cam is attached having a seat conforming to the contour of the cam to prevent rotation thereof when adjusted.

2. The combination with drive and driven members, of means for coupling the same while allowing for disalignment of said members, comprising rotatable heads having relatively radial adjustable movement therebetween, a cam carried by the coupling located between the heads and rotated therewith, said cam being of angular contour to provide multi-faced cam surfaces, means for rotatably adjusting the same, the head to which the cam is attached having a seat conforming to the contour of the cam to prevent rotation thereof when adjusted, and a threaded securing means engaging said head and passing through the cam to bind the latter to the head.

3. The combination with drive and driven members, of means for coupling the same while allowing for disalignment of said members, comprising rotatable heads having relatively radial adjustable movement therebetween, a cam carried by the coupling located between the heads and rotated therewith, said cam being of angular contour to provide multi-faced cam surfaces, means for rotatably adjusting the same, the head to which the cam is attached having a seat conforming to the contour of the cam to prevent rotation thereof when adjusted, and a threaded securing means engaging said head and passing through the cam to bind the latter to the head, the securing means having a headed portion impinging on the cam and forcing the same to its seat, the head projecting into a slotted portion of the opposite member to constitute the said means for allowing for disalignment of the coupling members.

4. The combination with separated drive and driven shafts having fixed axes of rotation, of means for coupling the same while allowing for disalignment of said shafts, comprising rotatable heads mounted on said shafts, one of said heads having a radial slotted portion constituting a way and the other of said heads having a stud projecting therefrom and into said way on a line offset from but parallel to the axis of the head carrying the same, and a cam carried by said stud located between the heads, said stud being in the form of a screw to clamp the cam to said other head to move therewith.
